UNITED STATES PATENT OFFICE.

HERBERT M. FRIENDLY, OF PORTLAND, OREGON.

TELEPHONE SYSTEM.

Application filed February 28, 1921. Serial No. 448,712.

The present invention has for its broad objects the facilitating of secret conferences on a so-called conference trunk in private automatic exchanges. However, as will appear, the features may also be applied in various ways to comprehensive exchanges, as well.

The invention in its specific form chosen for the illustration herein, contemplates a so-called two-wire common battery automatic telephone system as has been widely used, the present invention necessitating novel departures from equipments heretofore known, in attaining the new objects, while retaining certain operative functions which are known.

Conferences have been held between telephones of private automatic exchanges heretofore by the telephones forming the conference relation gaining connection with a commonly accessible trunk. Heretofore so far as I am aware in order that the various parties to the conference may gain simultaneous connection with the common trunk, the trunk is not made busy incident to it being seized by the first party gaining connection with it, or by any of the parties gaining connection with it subsequently successively. The practice has been, where conference trunks have been provided in private automatic exchange equipments, to have the conference trunk at all times accessible to all the connectors in two-figure capacity private branch exchanges, and accessible to all the first selectors in three-figure capacity private branch exchanges.

It is manifest from the foregoing that it will be impossible under the above method of conference operation to hold conferences that cannot be intruded upon by unauthorized persons through the telephones of the private branch exchange because they can unrestrictedly gain access to and connection with the conference trunk either before a conference has been called or after it is under way.

The present invention is particularly directed to provide means whereby the party calling the conference can, as heretofore practiced, request the parties desired in conference to each call the same predetermined number through the agency of the calling device at their telephones and thereby gain telephonic connection with the conference trunk. Now, under the new arrangement contemplated in the present invention the

party calling the conference (who will be hereinafter referred to as the supervisor or the supervising party), will at any time, either before or after the other parties (or single party only) have complied and are in common telephonic connection with a first branch of the conference trunk and with each other, call a second predetermined telephone number reserved exclusively to the supervising party, and thereby gain telephonic connection with a second branch of the conference trunk telephonically related to the other (first) branch of the conference trunk to which the other parties connect. After the supervising party ascertains that all the requested parties are on the first branch of the conference trunk and in telephonic connection with him, and, of course, knowing how many such parties there are, he will dial "1" for example and thereby initiate the functioning of a first hunting or setting-switch, which switch will in turn set up a condition in a second switch indicative of the actual number of parties connected with the said first branch and automatically return to normal position. He will then dial a digit indexing the number of parties ordered on the first branch of the conference trunk, whereupon the said first switch will be caused to step a corresponding number of steps, completing a circuit through the said second switch and to a tone-controlling relay which will apply a tone to the second branch of the conference trunk, audible to the supervising party. The said tone will be thus applied providing no more or no less parties are connected with the first branch of the conference trunk than indexed by the digit dialed.

If, upon attempting to verify the number of parties (or the single party thereon) on the first branch of the conference trunk, as set forth, the tone does not become audible, the supervising party will then know that some other party, unauthorized, is connected with the conference trunk, or that all supposed to be are not. Steps can then be taken to investigate. As will appear presently the tone is applied to the second branch audible to the supervising party secretly, not audible to the parties connected with the first branch, so the supervising party can have any investigations made while the condition found remains unknown to others.

In case the supervising party obtains the tone, indicative that the proper number of parties are in conference relation, dialing

digit "1" will cause the tone to cease and the conference can proceed secretly, and furthermore, the conference trunk will be barred from seizure thereafter, however, providing for any of the parties on the first branch of the conference trunk disconnecting therefrom without unguarding the conference trunk against its seizure subsequently, or in lieu of the disconnecting party.

The present invention also contemplates a feature, effective at will through the manipulation of switch elements. Under the alternative operative method, consequent upon the supervising party first calling digit "1" as before set forth, a specific tone source indicative of the number of parties connected with the common branch of the conference trunk will be secretly evidenced to the said supervising party. He can then call digit "1" and the tone will cease, so the conference can proceed.

Lamps are provided, located singly or in multiplicity visible to a certain party or parties, which will index the number of parties on the common branch of the conference trunk, depending upon which lamp or lamp set is glowing.

A step-by-step counting device is provided to integrate the number of busy test contacts encountered, the latter busy test contacts being indicative of the number of telephones connected to the first or common branch of the conference trunk.

Referring to the accompanying drawings: Fig. 1 shows a calling telephone leading to a pre-selector or so-called line-switch in access to a plurality of connectors, one connector only of which is shown;

Fig. 2 in conjunction with the right-hand portion of Fig. 1 shows a schematic representation of five connectors accessible to a conference trunk and other associated, cooperating equipments necessary in carrying out the present invention. It will be noted that Fig. 2 attaches to the right of Fig. 1 so that the lines extending toward the margins of the sheets register.

Fig. 3 which attaches to the right of Fig. 2 so that the lines extending towards the margins register, shows the busy contact counting device and register with means for applying tone sources as contemplated in the present invention.

Fig. 4 is a schematic detail plan view of one of the levels of contacts and its cooperating wiper shown in the automatic rotary switch elements F and G represented in Fig. 3. The elements F and G also have the function of step-by-step calling-device control.

To simplify the drawings and descriptions, the battery (which has its negative pole ungrounded), and ground are shown as independent sources throughout, wherever applied, but it is to be understood that the sys-

tem is of the common battery type. In the descriptions, when a circuit is traced to a winding the opposite terminal of which is shown applied to grounded battery or to ground, the described circuit is to be considered as traced to ground through the winding and battery, or direct to ground, as indicated.

Where a circuit is traced through an armature of a relay to an engaged contact, the contact only will generally be designated. That is, if the armature is attracted the make contact only will be referred to generally and if the armature is normal the resting contact only will be designated generally.

Referring again to the various figures:

In Fig. 1 the calling telephone T (of which there are a plurality in the system) is of the usual series type, having a calling device (sometimes termed a dial or sending device) of the general class, as shown in British patent 80 to Dicker, No. 29,654 of 1910. The pre-selector (also called a line-switch) PS is of the general class, as set forth in U. S. Letters Patent to Lamb, No. 1,193,160, granted August 1, 1916. The connector A is of the general class as set forth in U. S. Letters Patent to Deakin No. 1,164,479, granted December 14, 1915.

The said connector A has access to a plurality of bank contact sets on a plurality of levels. Usually ten levels would be provided, each having ten sets of bank contacts. The contacts shown are to be assumed as the last three sets of contacts of the first level. The connector A will function as a selector on certain levels, depending upon the adjustments of its off-normal spring sets 2 and 3. For example, if springs 2 and 3 are adjusted to close upon the shaft of the connector attaining the tenth level, upon which perhaps are outgoing trunk lines, the switch will, upon its shaft attaining the tenth level, forthwith start automatic rotation, seeking an idle trunk to seize. We are, however, not particularly concerned with the operation of the connector A functioning as a trunk-hunting selector, inasmuch as this function is not a function directly related to the present invention. However, the off-normal springs 2 and 3 are, in addition to the stated possible adjustment affecting the tenth level, arranged to close upon attaining the tenth rotary position when functioning on the first level. Of course, a supplemental set of springs in multiple relation to the sets 2 and 3 may be provided to operate independently of 2 and 3 by cam action from the shaft, when the switch is functioning on the first level.

Referring now to Fig. 2, B, C, D, and E each indicates a connector as shown in A of Fig. 1, and in addition, all the other cooperating elements shown in Fig. 1. It will thus be manifest that Figs. 1 and 2 represent a private automatic exchange system having a plurality of telephones of the stated type,

each connected with its individual pre-selector, and each said pre-selector has access to each of five connectors represented by A, B, C, D and E. Further, that each of the said 5 connectors has access to corresponding bank contacts commonly related to the two branches of the conference trunk.

It will be observed presently that as many 10 parties as the connector capacity will permit may gain connection with the first branch of the conference trunk used generally by the parties of the conference, but that only one party at a time can gain connection with the other (second) branch reserved to the supervising party at a random one of said telephones.

Referring to Fig. 3, switch F is a step-by-step switch having five wipers rigidly attached to its shaft, each wiper cooperating 20 with a level of six bank contacts spaced equally and directed radially from the circumference of an insulated holding element. A drive-magnet M upon being energized (or de-energized after energization) causes the five 25 wipers to advance one step into engagement with a successive set of five cooperating bank contacts, so that if six impulses are imparted to the shaft revolvably carrying the five attached wipers, through the agency of the 30 magnet M, the said wipers will have successively engaged each of its respective cooperating bank contacts and have arrived back upon their normal resting bank contacts. This function will be thoroughly understood 35 by referring to Fig. 4 and it may also be considered in more detail by referring to the cited patent to Lamb, the relationship between the magnet M and the shaft carrying the wipers being the same in switch F of the 40 present invention as set forth in the said cited patent. Excepting, however, that in the present invention it is preferred (though not necessary) to have the wipers driven forward consequent upon the de-energization of 45 the motor magnet M and the motor magnet M', rather than upon their energization.

Off normal spring group designated ON3 operates consequent to any off-normal movement of the wipers of switch F.

50 Switch G is a similar switch to switch F in its general mechanical functioning, however, having but two wipers and cooperating levels of bank contacts.

It is thought that in view of the foregoing 55 general descriptions the operation of assumed set up connections and the invention itself will be clearly understood.

Assuming that a conference in which three 60 parties and the supervisor is to be held. The supervisor will instruct (by calling over the telephone or otherwise) the three parties to come on the conference trunk, which they will each do by calling telephone number "19". For example, when party at telephone T 65 removes the receiver from the switch-hook

to initiate the call, pre-selector PS will seize the common trunk leading to connector A. A circuit can now be traced from upper winding of relay N, conductor 5, spring 6, conductor 7, wiper 8, conductor 9, through telephone 70 T, conductor 10, wiper 11, conductor 12, contact 13, conductor 14 to the lower-winding of relay N, causing it to actuate. A circuit can thereafter be traced from the winding of slow-releasing relay B, armature 15, conductor 75 16, to grounded armature 17, causing said relay B to actuate. This will apply ground from contact 18 to conductor 19, wiper 20 to the winding of the cut-on relay of the pre-selector PS, to disassociate the line-relay of 80 the pre-selector, in a manner well known. Upon the party at telephone T manipulating the calling device thereat to effectuate one open impulse constituting digit "1", relay N will deactivate and reactuate one time, applying ground from armature 17, conductor 85 16, armature 15, contact 21, side-switch wiper 22, winding of relay C, winding of the vertical magnet V, side-switch wiper 23, to grounded battery, causing the vertical magnet 90 to step the shaft of the connector carrying wipers 24, 25 and 26 one vertical step and into registry with the first level of bank contacts. At the time the vertical magnet is energized slow-releasing relay C actuates 95 and applies ground from its armature 27 to the winding of the private magnet P, causing it to attract its armature preparatory to permitting the side-switch wipers 22, 23 and 28 100 to move into their second positions respectively, consequent to its deenergization and the retraction of its armature resultant thereto. The latter occurs the period of relay C following its de-energization upon the re-establishment of the energizing circuit for 105 relay N upon the calling device at telephone T returning to normal. Upon the party at the calling telephone T transmitting digit "9" in the manner as before, this time effectuating nine open impulses wherein relay N will deactivate and reactuate nine times consequent thereto, a circuit will be established upon each retraction of relay N from grounded armature 17, conductor 16, armature 15, contact 21, wiper 22 (in second position) winding 110 of relay C, armature 29, winding of rotary magnet R, side-switch wiper 23 to grounded battery, causing the rotary magnet to step the shaft in nine rotary steps, wipers 24, 25 and 26 engaging bank contacts 30, 31 and 32 115 respectively. Bank contact 30 has battery potential on it, received through resistance 201 over conductor 202. Upon the retraction of relay C, its period after its last energization impulse private magnet P will deactivate as before and permit the side-switch wipers 22, 23 and 28 to advance into their 120 third positions respectively. A circuit can now be traced from bank contact 30 (upon which is battery potential), wiper 24, side- 125 hook 130

switch wiper 28, inside winding of relay H, contact 33 of private magnet, armature 34, conductor 19 to grounded contact 18, causing relay H to actuate and lock its outside winding to armature 35 and to grounded conductor 19. Contact 36 will become grounded upon armature 35 applying ground to side-switch wiper 28, wiper 24, bank contact 30, conductor 202 to bank contact 203. A circuit 5 can now be traced from signalling current generator G', armature 37, conductor 38, armature 39, conductor 40, contact 41, wiper 26, bank contact 32, conductor 42, retardation coil 205, armature 204, conductor 206, 10 bank contact 31, wiper 25, conductor 43, armature 44, conductor 45, armature 46, conductor 47, contact 48, contact 49, to the inside winding of relay F, causing relay F to actuate. Relay F is so designed as to not actuate. Relay F is thus included in a signal circuit 15 including a condenser, as for example when ringing upon conductors including a telephone similar to T. A telephonic circuit can now be traced from telephone T to spring 6, as described, condenser 50, conductor 51, armature 52, conductor 53, contact 48, conductor 47, armature 46, winding of shunted relay G'', wiper 25, bank contact 31 to conductor 206 and from conductor 42, bank contact 32, 20 wiper 26, contact 41, conductor 40, armature 39, conductor 38, armature 37, conductor 55, condenser 56, contact 13 to the telephone T over the circuit described.

It will next be assumed that connectors B and C (bearing in mind that they are similar to connector A and that they are accessible to telephone similar to T and line switches similar to PS respectively), are manipulated as described in relation to connector A and that, therefore, wipers 207, 208, and 209 are in engagement with bank contacts 210, 211, and 212 respectively and that the conductors 42 and 206 are in telephonic relation with the telephone leading to connector B. Also 40 wipers 213, 214 and 215 are in engagement with bank contacts 216, 217, 218 respectively and that the conductors 42 and 206 are in telephonic relation with the telephone leading to connector C. Therefore, telephone T 45 and the two similar telephones leading through connectors B and C respectively are in telephonic relation through the common trunk conductors 42 and 206 and that parties thereat may converse mutually audible. 50

It will be assumed that connector A is in normal position and that the party gaining telephonic connection from telephone T through it to the trunk conductors 42 and 206 had gained connection through the telephone and pre-selector leading to connector D and that wipers 219, 220, and 221 were in engagement with bank contacts 222, 223 and 224 respectively and that, therefore, the telephones connected through connectors B, C 55

and D respectively are in telephonic relation 65 mutually audible.

It will now be assumed that the party calling or supervising the conference is at telephone T and that he manipulates the calling device thereat to effectuate telephone number "10". The connector A will function in a manner as before described when the calling device was manipulated to effectuate telephone number "19". However, the wipers will have been moved to the tenth rotary position along the first level in lieu of to the ninth position thereon. It will be borne in mind that off-normal spring sets 2 and 3 are designed to close their contacts upon the wipers rotating to the tenth rotary position on the first level, and therefore, these contacts will now be closed. Wipers 24, 25 and 26 are in engagement with bank contact 60, 61 and 62 respectively. Relay J will actuate due to the closure of off-normal spring set 2. An inert circuit path can now be traced from battery through resistance 225, conductor 226, bank contact 60, wiper 24, side-switch wiper 28 in second position, armature 63, spring 64, to the winding of the private magnet, 70 the private magnet not energizing, and therefore retracting consequent to the retraction of armature 27, as before described. This will permit the side-switch wipers 22, 23 and 28 to advance into their third 75 positions respectively and cause relay H to actuate as before described. A circuit can now be traced from grounded contact 18, conductor 19, armature 35, contact 65, armature 66 through off-normal spring-set 3 to the winding of relay K, causing it to actuate. A circuit can now be traced from the lower winding of relay 230, conductor 231, bank contact 61, wiper 25, winding of 80 shunted relay G'', armature 46, conductor 47, spring 6, conductor 7, through the telephone T, conductor 12, armature 39, conductor 40, contact 41, wiper 26, bank contact 62, conductor 68 to the upper winding of relay 230, causing said relay 230, and also relay G'' in the 85 connector A to actuate. A circuit can now be traced from the winding of relay B to grounded armature 69. The latter will ensue before the period of relay B which deenergized 90 dependent upon relay N which was disassociated from its described energizing circuit consequent to the actuation of relay K. Ground will thus be maintained from grounded contact 18 to conductor 19 and to the outside locking winding of relay H, dependent upon relay G''. At the time relay 230 actuates it applies its grounded armature 232 to the contact leading to the winding of the slow-releasing relay 233, causing it to actuate.

It is thus manifest that a telephonic circuit now exists from telephone T to conductors 231 and 68 and that relay 230 is energized in series with the telephone T and is 100 105 110 115 120 125

therefore in control of the calling device at telephone T. It will be further noted that conductors 42 and 206 are related telephonically to conductors 68 and 231 through condensers 234 and 235 respectively, and therefore, the telephone T and the telephones (not shown) assumed connected to the trunk conductors 42 and 206, through connectors A, B, C and D respectively, are in telephonic connection mutually and that a conference between the parties through the said telephones may proceed.

After the supervising party at telephone T has satisfied himself that the three parties called into the conference are present with him on the conference trunk (42 and 206) he will dial digit "1", whereupon relay 230 will deactivate and reactuate one time, applying ground from its armature 232 to armature 236, winding of slow-releasing relay 237, conductor 238, to the winding of motor magnet M, causing it to actuate and advance wipers 239 to 243 inclusive one rotary step, into engagement with bank contacts 203, 244 to 247, inclusive respectively.

It was described how bank contact 203 became grounded consequent to connector A seizing after its wiper 24 engaged bank contact 30 and it may be stated here that bank contacts 248, 249 and 250 become grounded similarly consequent to connectors B, C and D seizing as set forth herein. It is to be remembered here that bank contact 203, under the assumed condition now existing does not constitute ground potential, because wiper 24 is assumed to be in engagement with bank contact 60 in lieu of bank contact 30 first assumed so that bank contacts 248, 249 and 250 are the only bank contacts constituting ground potential engageable to wiper 239.

Upon the motor magnet M causing the wipers 239 to 243 inclusive, to advance into engagement with contacts 203, 244 to 247 inclusive, respectively, the following condition will ensue, bearing in mind that bank contact 203 has battery potential, derived through resistance 201; ground from armature 251, conductor 252, wiper 240, bank contact 244, conductor 253 to the winding of relay 254 will energize the latter relay and cause it to actuate. A locking circuit for relay 254 is closed from its winding, contact 262 to grounded conductor 252. In view of the slow-releasing characteristic of relay 233, it will remain sustained, after it becomes actuated, over all lapses of ground from armature 232 such as will occur upon relay 230 responding to manipulations of the calling device at telephone T and therefore, the ground applied from armature 251 to conductor 252 will endure until the circuit including the windings of relay 230 is open for a prolonged period, as for example, by the supervising party at telephone T restoring the receiver on the switch-hook. Contacts 60, 263 to 266 in-

clusive, attached to common conductor 226 will, of course, constitute ground potential, thus guarding the supervisor's branch of the conference trunk against intrusion by reason of connector A maintaining ground potential 70 on wiper 24 (and engaged bank contact 60), in the manner set forth hereinbefore. Ground from armature 267, conductor 268, bank contact 246, wiper 242, armature 269 to the winding of motor magnet M will cause the said motor magnet to automatically actuate and advance the wipers 239 to 243 inclusive a rotary step into engagement with bank contacts 248, 270 to 273 inclusive respectively. Consequent to the actuation of the motor magnet M, its 80 armature 269 will attract from its resting contact and open its described energizing circuit, causing it to deactivate and reestablish its energizing circuit, whereupon it will again actuate, advancing the said wipers 239 to 243 85 inclusive, an additional rotary step into engagement with bank contacts 249, 274 to 277 inclusive respectively, whereupon the same functioning of the motor magnet M as described will again ensue, advancing the said 90 wipers one rotary step; this functioning continuing until the said wipers have left bank contacts 278 to 282 inclusive respectively and have engaged the respective bank contacts upon which they normally rest, as shown in 95 the drawing.

Due to relay 254 being locked as described, a circuit path now exists from wiper 241, contact 262 to grounded conductor 252; this circuit becoming established upon relay 254 actuating incident to the wiper 240 engaging bank contact 244, so that normally wiper 241 constitutes battery potential derived through the relay 254. However, upon wiper 241 returning to and engaging the bank contact 100 upon which it normally rests, it will apply its ground potential over conductor 283 to the winding of relay 284, causing it to actuate and lock through its contact 285 to grounded conductor 252. A circuit can now be traced from 105 the winding of relay 286 to grounded armature 267, causing it to actuate, and apply ground from conductor 287 to conductors 288 to 292 inclusive, applying this ground potential to bank contacts 203, 248, 249, 250 and 278, 110 also to connector bank contacts 30, 210, 216, 222 and 293 in lieu of battery potential normally existing on the said contacts. It will thus be seen that the bank contacts of the conference trunk, (conductors 42 and 206) are 115 now guarded against seizure by any connector normally accessible thereto in plurality, and that therefore, only those attaining connection with the conference trunk previous to the supervising party dialing digit "1", 120 from telephone T, can gain connection with it; this until the said supervising party at telephone T restores the receiver thereat on the switch-hook and causes relay 233 to deactivate and unlock relay 286.

It has been set forth that bank contacts 248 to 250 inclusive, constituted ground potential before relay 286 actuated, resultant to the actuation of relay 284; this due to bank contacts 210, 216 and 222 having been seized by connectors B, C, and D. With this latter in mind it will be clear that when the motor magnet M drove the wipers 239 to 243 inclusive, wiper 239 derived ground potential 10 successively from contacts 248, 249 and 250 and communicated this ground series over conductor 294, contact 295 to the winding of motor magnet M', causing it to actuate and deactivate three times, stepping its wipers 15 296 and 297 into engagement with bank contacts 298 and 299 respectively.

It may be mentioned here that the object of including conductor 294 through relay contact 295 is to insure that no impulses can be 20 imparted to the winding of magnet M' after the relay 284 actuates. Otherwise, when magnet M is caused to step controllably, responsive to each impulse applied from armature 232, magnet M' would actuate upon wiper 25 239 again encountering the grounded bank contacts engaged in its travel in the cycle completed automatically after its initial impulse, as set forth.

By reference to Fig. 4 it will be manifest 30 that the contacts are successively engaged and that the wiper does not engage adjacent contacts co-incidently. It may be further stated here that the described movement of the sets of wipers driven by the motor magnets M and M' respectively, are driven rotarily consequent upon the armatures of the said motor magnets retracting upon de-energization, though it is entirely practicable to have the wipers driven consequent upon 40 the energization directly. Thus, it will be manifest from the foregoing that upon the supervising party dialing digit "1" the switch F will, responsive thereto, advance one rotary step and then automatically advance by 45 steps until it reaches its normal position. At the same time, switch G will cause its wipers to be advanced as many rotary steps as there are grounded bank contacts engaged by wiper 239 in its cycle. That is to say, the 50 wipers of switch G will be advanced as many rotary positions as there are connectors in engagement with the conference trunk, not counting the connector A on the second branch controlled from telephone T by the 55 supervising party.

There being three parties to the conference, exclusive of the supervising party, the supervising party will now manipulate the calling device at his telephone T to effectuate three 60 open impulses constituting digit "3" which latter digit indexes the number of parties in the conference excluding the supervising party. At each open impulse, relay 230 will deactivate and then reactuate upon the closure, applying ground from its armature 232,

armature 236, winding of relay 237, conductor 238 to the winding of motor magnet M, causing the said motor magnet to be energized and de-energized three times, thereby stepping the wipers 239 to 243 inclusive, three 70 rotary steps into engagement with bank contacts 249, 274 to 277 inclusive respectively. It will be noted here that conductor 268 does not now constitute ground potential and that, therefore, the automatic interrupter circuit 75 for motor magnet M described before as leading to armature 269 is now open at armature 267. After the period of relay 237 a circuit can be traced from grounded armature 300, wiper 296, bank contact 298, conductor 301, 80 bank contact 277, wiper 243, conductor 302, contact 303 to the winding of relay 304, causing it to actuate. A circuit can now be traced from tone source T2, conductor 305, switch arm 306, spring 307, conductor 308, 85 armature 309, conductor 68 over the described path including the telephone T to the lower winding of relay 230, audible to the supervising party. It will be noted here that due to armatures 309 and 310 being attracted 90 the links between the branches of the conference trunk including condensers 234 and 235 will be open, and therefore, the tone will not be audible to the parties called into the conference (and any intruding party) connected 95 with the first branch, conductors 42 and 206.

The tone received by the supervising party will indicate or verify that there are but three parties on the conference trunk exclusive of the supervising party. It is clear that if the 100 supervising party had ordered four parties in on the conference, but only the three exemplified complied, and that the supervising party, therefore, in verifying, dialed digit "4" in lieu of digit "3", as before, wiper 105 243 would be caused to rest on bank contact 312 in lieu of bank contact 277, and therefore, in view of the position of wipers 296 and 297 on bank contacts 298 and 299 respectively, the described circuit from grounded armature 300 to the winding of relay 304 would not be completed, and that therefore, due to the tone not being received the supervising party would know that the parties 110 were not all present, or as shall be clear presently, that some unauthorized party had gained connection with the conference trunk. It may be stated here that in lieu of the supervising party dialing digit "3" or digit "4", as exemplified, he could dial digit "1" successively until he obtained a tone. Then, the 115 number of times that he dialed digit "1" would index the number of parties in on the conference trunk, exclusive of himself, that is, the number of telephones connected to 120 the first branch of the conference trunk.

We will assume that an unauthorized party had gained connection with the conference trunk through connector E and that, therefore, wiper 313 caused bank contacts 130

293 and 278 to constitute ground potential; this before the actuation of relay 286. Then, wiper 239 will encounter four grounded bank contacts in lieu of three, as before described 5 and that therefore, four ground impulses will be applied to the winding of motor magnet M' causing it to advance its wipers 296 and 297 into engagement with bank contacts 314 and 315 in lieu of bank contacts 298 and 299 10 respectively. Now, upon the supervising party dialing digit "3" (or digit "1" three times successively) the circuit from grounded armature 300 will not be completed, because wiper 243 will rest on bank contact 277. If 15 now, the supervising party dials digit "1", causing wiper 243 to advance and engage bank contact 312, the circuit from grounded armature 300 will complete its circuit from wiper 296, bank contact 314, conductor 316, 20 bank contact 312, wiper 243, conductor 302, contact 303 to the winding of relay 304. The relay 304 will actuate and apply the tone T2 audible to the supervising party as set forth before. This will verify that there are four 25 parties on the conference trunk, whereas he had ordered but three to come thereon, and that, of course, steps may be taken to locate the intruder.

From the foregoing it is manifest that if 30 only the three authorized parties are on the conference trunk the tone will index the fact. This tone will continue audible until the supervising party dials digit "1" to cause motor magnet M to advance its wipers one rotary 35 step, thereby opening the traced path including the winding of relay 304 and causing it to deactuate and reestablish the conference relation and disconnect the tone source T2 so that the conference may proceed. It will be 40 obvious that in practice the supervising party may after dialling digit "1" to initiate the functioning of switch F, follow by dialling digits "1" successively until a tone is obtained. Then, the number of times digit 45 "1" is dialed to attain the tone condition after initiating the movement as stated, will index the number of parties on the first branch of the conference trunk.

It will be manifest, presently, that the supervising party can, in lieu of dialling digit 50 "1" to disassociate the verifying tone, replace the receiver upon the switch-hook and then initiate a new call and come in on the second branch of the conference trunk as before, by dialing "10". In this connection it may be 55 mentioned that had the supervising party not dialed digit "1" to initiate the movement of switch F, but had simply replaced the receiver on the switch-hook, upon the deactuation of relay 230 a circuit would become completed from grounded armature 232, armature 236, winding of relay 237, conductor 238 to the winding of motor magnet M, causing the wipers to be stepped one rotary position, 60 completing a circuit from grounded arma- 65 ture 267, conductor 268, bank contact 246, wiper 242, armature 269 to the winding of the motor magnet M, causing it to actuate and break its energizing circuit and advance the wipers 239 to 243 inclusive an additional 70 rotary step, whereupon the same functioning will take place as hereinbefore described causing the shaft to complete a cycle and return to its normal position as shown in the drawing. 75

Relay 237 is not essential to the carrying out of the salient operative features of the present invention. It is introduced to insure that the path traced including the winding of relay 304 shall not become closed until 80 a brief period after wiper 243 of switch F engages a cooperating bank contact. This period is approximately the period of relay 233. Relay 237 will thus sustain over the current lapses of a digit series, so there can be 85 no brief period of confusing tone applied by the action of relay 304 audible to the supervising party, should a circuit condition including the winding of relay 304 be possible before the wipers of switch F have come to 90 final rest consequent upon the supervising party sending the second digit indexing the number of parties instructed to come on the conference trunk. This condition could occur if but three of the four instructed parties 95 came on the conference trunk. That is, as the wiper 243 engages and passes contact 277 in reaching bank contact 312 while wiper 296 is resting on bank contact 298, the path including the winding of relay 304 will be momentarily completed from grounded armature 300, wiper 296, bank contact 298, conductor 301, bank contact 277, wiper 243, conductor 302, causing relay 304 to actuate and apply the tone as before set forth, audible to 100 the supervising party. It will be noted that when the tone is applied audible to the supervising party that the link between conductors 68 and 42 including condenser 234 and the link between conductors 206 and 231 including condenser 235 will be opened at armatures 309 and 310 respectively. Thus, while 105 the supervising party is verifying, those on the conference trunk will not hear the tone. 110

Retardation coil 205 is removed from the bridge incident to the actuation of relay 284, and therefore does not derive current during the period of the conference. It may thus be of low ohmic obstruction to insure the ring-cut-off relays (as F) operating while 115 current from retardation coils (as U) of other seized connectors is being derived through it.

We will now assume that after the conference has been completed with the three authorized parties that the supervising party restores his receiver on the switch-hook, relay 230 deactuating, followed by its dependent relay 233 its period thereafter. A circuit can 120 now be traced from grounded armature 251, 125

to conductor 320 and to the bank contacts 321, 315, 299, 322 and 323. Bearing in mind that wiper 297 is assumed in engagement with bank contact 299, this circuit is contained 5 through armature 317 to the winding of motor magnet M', causing it to energize and attract its said armature 317 and open the said energizing circuit, whereupon wiper 297 will advance into engagement with bank contact 10 315, causing the said described energizing circuit of motor magnet M' to again be established and interrupted, driving wiper 297 into engagement with bank contact 321, thus again establishing the energizing circuit of 15 motor magnet M' whereupon it will actuate and interrupt and drive wiper 297 into engagement with bank contact 324, upon which it normally rests, having thus completed its cycle.

20 Due to ground having been removed from conductor 252, by the retraction of armature 251, the locking ground of relays 286, 254 and 284 is removed and the said relays retract. However, we are concerned chiefly at this 25 juncture with the retraction of relay 284 which will establish a circuit from grounded armature 267, conductor 268 to bank contacts 281, 319, 276, 272 and 246. Remembering that wiper 242 now rests on bank contact 319 30 (it having been stepped from bank contact 276 to cease the tone), the circuit may be traced to wiper 242, armature 269 to the motor magnet M, causing it to energize and attract its armature 269 and incidentally interrupt the said circuit, whereupon it will retract and advance wiper 242 into engagement with bank contact 281, re-establishing the energizing circuit to the said motor magnet M, causing it to function as last before 35 described, this time advancing wiper 243 into engagement with bank contact 325, which is its normal resting position. It will thus be noted that upon the retraction of relay 233, motor magnets M and M' will start automatically functioning and so continue until they 40 have caused their respective cooperating sets of wipers to have attained their normal positions.

It will be clear that during the progress of 50 the conference, after the supervising party, in verifying, causes relay 286 to actuate and apply a guarding ground potential on the private bank contacts of the first branch of the conference trunk accessible to the various 55 connectors, that this guarding ground potential endures until the said relay is caused to deactivate as set forth, and, therefore, no party can gain connection with either branch of the conference trunk under the condition. 60 However, the release of each connector is individually controlled by its governing telephone, it can therefore be released from the conference connection by the party controlling it restoring his receiver upon the switch-hook, but due to the relay 286, being inde-

pendently held actuated dependent upon relay 230, the private bank contact in access to a released connector does not now become ungrounded until the supervising party restores his receiver on the switch hook at telephone 70 T. Thus, a party to the conference once withdrawing cannot again obtain connection therewith.

It will be assumed now, that the alternative operative method referred to at the outset is 75 to be used, temporarily, perhaps. Switch-arm 306 will be opened and switch-arm 330 will be closed. Before going into the next operative description attention will be called to the fact that after the period of relay 237 80 has elapsed after wiper 296 stops on an engaged bank contact, 298 for example, a circuit can be traced from grounded armature 300, wiper 296, bank contact 298, conductor 301 to the winding of relay 331 and the free terminal of lamp 332, causing the said relay to 85 actuate and the said lamp to glow.

After the supervising party believes the parties ordered in conference have come in on the first branch of the conference trunk and 90 he has called digit "1", causing switch element F to function one cycle and then rest at normal, causing switch element G to advance as described until its wipers 296 and 297 rest on bank contacts 298 and 299 respectively due 95 to three parties having connected with the first branch of the conference trunk and wiper 239 having encountered three grounded bank contacts, the following circuit condition will ensue upon the retraction of relay 237: 100 Ground from armature 267, off-normal spring 337, conductor 302, contact 303, to winding of relay 304, causing it to actuate. Also, ground from armature 300 will cause relay 331 and lamp 332 to energize as set forth. A 105 tone will be applied from source T2, conductor 305, interrupter 340, contact 341, conductor 342, switch arm 330, spring 307, conductor 308, armature 309, conductor 68 and over the before described tone path audible to the 110 supervising party.

It will be manifest that had wiper 239 encountered four bank contacts in lieu of three, and therefore wiper 296 rested on bank contact 314, the described circuit path from 115 grounded armature 300 would be continued to energize relay 343 and lamp 344 in lieu of relay 331 and lamp 332, and the described tone path from tone source T2 and conductor 305 to conductor 342 would be by way of interrupter 345 in lieu of 340. The latter interrupter and lamp is each indicative of four 120 busy test bank contacts having been encountered by wiper 239, and that there are four telephones connected with the first branch of 125 the conference trunk. A corresponding functioning indexing the number of busy bank contacts wiper 239 encounters will ensue upon wiper 296 engaging any of its bank contacts 346, 347 or 348, causing relays 349, 130

350 and 351 to actuate, and lamps 352, 353 and 354 to energize, deriving tone current through interrupters 356, 357 and 358 respectively.

5 The established tone path described including the switch-arm 330 will endure and relay 304 will remain actuated until the supervising party calls digit "1" (or other digit not indexing the number of busy test contacts engaged by wiper 239) and causes off-normal springs of set ON3 to operate and open the traced circuit energizing relay 304 and also the tone path at spring 307, causing the tone to be disconnected from the second branch of 10 the conference trunk and the first and second branches of the conference trunk to be established in conference relation.

It is manifest that if switch 306 is left in its operative position no confusion will arise 20 as switch F must be in off-normal position to make tone through said switch-arm 306 effective. Therefore, if in lieu of the said calling of digit "1" to cause the applied tone to cease, digit "3" (assuming that three grounded test 25 contacts were engaged by wiper 239 and therefore wiper 296 rests on the bank contact 298) were called upon the retraction of relay 237 a circuit from winding of relay 304, contact 303, conductor 302, wiper 243, bank contact 277, conductor 301, bank contact 298, wiper 296 to grounded armature 300 would be established, causing relay 304 to actuate. Then, tone from source T2, conductor 305, switch-arm 306, spring 307, conductor 308, 30 armature 309 to conductor 68 and over the before described path audible to the supervising party will ensue. This tone being uninterrupted will now serve as a check upon the interrupted tone obtained by the first calling 35 digit "1" and thereby holding open the last traced energizing path of relay 304.

A counting device of meter RM is energized every time motor magnet M' is energized, the 40 windings of said meter RM and motor magnet M' being in multiple relation. The counter RM, may be one of the well known forms of electro-magnetic counters, with the addition of the restoring button 361. The latter said button when depressed disengages the 45 pawl 362 and causes the indicating member to retract to normal through the agency of a retracting spring 363. In other words, a button 361 is provided for resetting the 50 counter to zero at will.

55 In view of the foregoing, it will be manifest that present invention has wide adaptations in the art, of course, modified in details of design depending upon its application. For example, one use would be to have wiper 239 accessible to private bank contacts of trunks. Then, by operating relay 230 (perhaps independent of a telephone circuit) directly from a calling device the operator can 60 ascertain audibly or by reference to the lamps

or the counting device RM the number of 65 busy trunks in the tested group, in fact in the present exampled instance the bank contacts engageable by wiper 239 may be assumed to be the private contacts of a plurality of 70 trunks. Of course, employing the present invention in part only or as an amplification will be considered in view of and within the scope of the subjoined claims.

In the descriptions and in the drawings the 75 connectors have all been assumed as accessible to local telephones in the private automatic exchange. It will be manifest that this may also apply to connectors, such as trunk connectors that are not accessible to the local 80 telephones directly, but are also accessible 85 from telephones gaining connection with the private automatic exchange through the main office over a trunk line. In such an event, the multiples shown as appearing accessible to the local connectors will be multiplied, accessible 90 to the trunk connectors as well. Thus, secret conferences may be held, not only between parties connected directly with the private automatic exchange, but may include a party or parties directly connected over a 95 trunk with the main exchange as well.

The connectors A, B, C, D, and E are of a type which will not seize a set of bank contacts the private bank contact of which constitutes ground potential, and further, that 95 will not seize unless the private bank contact constitutes battery potential, however, applying ground potential to the private bank contact (and its multiples) incident to the seizure. Connectors of well known types (and 100 selectors as well), designed to seize upon not encountering ground potential and not being dependent upon receiving battery potential in order to seize, may be employed, introducing such obvious changes in the circuits (as the 105 removal of the resistances disposed similarly to 201) as will adapt them.

Having thus described an exampled form of one organization of the present invention, what I claim as new and desire to secure 110 by U. S. Letters Patent is:

1. In a telephone system, telephone lines, means for effecting a common talking connection between a plurality of said lines, and means solely controlled over one of said lines 115 for determining the number of lines connected together.

2. In a telephone system, telephone lines, automatic switches controlled over said lines respectively for effecting a common talking 120 connection between a plurality of said lines, and means for determining from one of said lines the number of lines connected together.

3. In a telephone system, telephone lines, means specific to each said line and controlled therefrom for effecting a talking connection 125 between a plurality of said lines and a common line upon request of a supervisor, and

means whereby the supervisor can determine from one of the connected lines the number of lines connected together.

4. In a telephone system, telephone lines, means for effecting a common talking connection between a plurality of said lines upon request of a supervisor, and means for automatically transmitting a signal over one of said lines to the supervisor if the number 10 of lines requested are so commonly connected together.

5. In a telephone system, telephone lines, means for effecting a common talking connection between a plurality of said lines upon 15 request of a supervisor, and means including automatic switch mechanism operated by the supervisor after the said connection has been effected for testing to determine whether the number of lines requested are so commonly 20 connected together.

6. In a telephone system, telephone lines, means for effecting a common talking connection between a plurality of said lines upon 25 request of a supervisor, a testing switch for counting the connected lines, means including the testing switch whereby the supervisor can determine from one of the connected lines the number of lines connected together, and for preventing additional lines from connecting 30 with the common connection.

7. In a telephone system, a plurality of 35 telephones and cooperating switches, a trunk normally accessible to the said telephones through the said switches simultaneously, and control means whereby one of the 40 telephones having attained connection with the trunk may thereafter at will prevent any other telephone thereafter attaining connection with the trunk.

45 8. In a telephone system, a plurality of telephones and cooperating automatic switches, a trunk normally accessible to the said telephones through the said switches simultaneously, and a tone source under positive directive control of one of the telephones connected with the trunk for applying the tone source 50 audible to the latter telephone for verifying the number of telephones so connected.

55 9. In a telephone system a plurality of telephones and cooperating automatic switches, a trunk normally simultaneously accessible to a plurality of the said telephones through the said switches, a tone source, a first step-by-step switch and a second step-by-step switch, control means for causing the first 60 step-by-step switch to automatically operate and cause the said second step-by-step switch to advance as many steps as there are telephones connected with the trunk, less one, and means for then causing the first step-by-step switch to operate responsive to the control means whereby the tone source may be applied through a circuit path set up by the operation of the step-by-step switches audi-

ble through one of the telephones connected 65 with the trunk.

10. In a telephone system, a plurality of telephones and cooperating automatic switches, a common trunk normally accessible to any 70 number of the said telephones simultaneously through the said switches respectively, a branch of the said trunk accessible to one of the said telephones through any one of the said switches, a tone source, a first and a second setting switch, control means at the 75 telephone connected to the said branch for causing the said first switch to automatically operate and thus cause the second said switch to advance as many steps as there are telephones connected to the common trunk, and means for then causing the said first setting switch to operate in response to the control means whereby the tone source may be applied over a circuit path set up by the operation of the setting switches audible to the 80 telephone on the branch.

85 11. In a telephone system a plurality of telephones and cooperating switches, a trunk consisting of a first and a second branch normally accessible to the said telephones simultaneously, a tone source, a first and a second setting switch, means for a plurality of the telephones gaining connection with the said first branch and for one of the telephones 90 only gaining connection with the said second branch, control means operable from the telephone gaining connection with the said second branch whereby the said first switch will be caused to operate and set up a condition in the said second switch indicative of 95 the number of telephones connected with the said first branch, means controllable through the second branch for causing the said first switch to operate and set up a condition in the said second switch indexing the number 100 of telephones connected to the said first branch and means for applying the tone audible to the party on the said second branch if the number of telephones on the said first branch corresponds to the condition set up 105 in the said second switch by the said first switch.

110 12. In a telephone system a plurality of telephones and cooperating switches, a trunk consisting of a first and a second branch normally accessible to the telephones, a tone source, a setting device, means in control of a telephone on one of the said branches for setting up a condition in the setting device 115 indexing the number of telephones on the other said branch, and means including the setting device whereby the tone will be applied audible through the controlling telephone, verifying the number of telephones 120 connected to the other said branch.

125 13. In a telephone system a first switch for testing the busy or idle state of a plurality of test contacts, a second switch cooperating with

- the said first switch which will function in correspondence with the busy conditions found by the said first switch but not the idle conditions found thereby, and means including the second switch for evidencing the number of test contacts found busy by the said first switch.
14. In a telephone system a testing telephone, a first switch for testing the busy or idle state of a plurality of test contacts, a second switch cooperating with the said first switch, which second switch will function in correspondence with the number of test contacts found busy by the said first switch but not the idle conditions found thereby, and means including the second switch controllable from the testing telephone for ascertaining the number of test contacts found busy by the said first switch.
15. In a telephone system a conference trunk having two branches in normal talking relation, a plurality of telephones having access to both branches of the said trunk, means so each of a plurality of the said telephones can independently gain connection with a first branch of the said trunk simultaneously, means so but one of the said telephones can independently gain connection with a second branch of the said trunk, and means controlled by the telephone gaining connection with the said second branch for thereafter at will guarding the said first branch against subsequent seizure.
16. In a telephone system a conference trunk, a plurality of telephones having access to the trunk simultaneously, and means controlled by a telephone connected with the trunk for thereafter at will guarding the trunk against subsequent seizure.
17. In a telephone system a conference trunk, a plurality of telephones having simultaneous access to the trunk through switches cooperating with sets of bank contact sets, and means controlled by one of the telephones connected with one of the sets of bank contacts for thereafter at will guarding any of the unseized sets of bank contacts against seizure.
18. In a telephone system a testing telephone, a switch for testing the busy or idle state of a plurality of trunk test contacts, a means controlled by the first switch for recording by its set-up condition the number of test contacts found busy by the switch but not the idle conditions found thereby, means including the second switch for initiating the functioning of the switch, and means for evidencing the number of test contacts found busy.
19. In a telephone system a plurality of telephones and cooperating automatic switches, a common trunk normally simultaneously accessible to the said telephones through the said switches, a tone source, a plurality of sets of trunk test terminals, a testing switch, a recording device, means for initiating the functioning of the testing switch and for causing the recording device to set-up a condition indicative of the number of sets of busy trunk terminals tested by the testing switch, and means including the tone source for indicating the number of sets of busy test terminals tested.
20. In a telephone system a plurality of telephones and cooperating automatic switches, a common trunk normally simultaneously accessible to the said telephones through the said switches, indicating lamps, a plurality of sets of trunk test terminals, a testing switch, a recording device, means for initiating the functioning of the testing switch and for causing the recording device to set up a condition indicative of the number of sets of busy trunk terminals tested by the testing switch, and means including the indicating lamps for indexing the number of sets of busy test terminals tested.
21. In a telephone system a conference trunk simultaneously accessible to a plurality of telephones through connecting means, a tone source, a test switch, means under control of a first telephone connected with the trunk for initiating the functioning of the test switch, and means automatically controlled by the test switch for applying the tone source audible to the said first telephone to index the number of telephones connected on the conference trunk.
22. In a telephone system a conference trunk simultaneously accessible to a plurality of telephones through connecting means, a tone source, a test switch, means under control of a first telephone connected with the trunk for initiating the functioning of the test switch, and means automatically controlled by the test switch for applying the tone source audible to the said first telephone to index the number of telephones connected on the conference trunk and for guarding the trunk against further connection.
23. In an automatic switching system, a calling line, a switch, a calling device, means for connecting the calling line with the switch, means controlled by the calling device for initiating the primary movement of the switch from normal position while maintaining the connection whereby the switch will then self automatically restore to normal position, and means effective consequent upon the said operation for disabling the said self-automatic operation and rendering the switch subject to step-by-step directive control from the calling device.
24. In a testing system, a calling line, a connecting switch, a testing switch, a calling device on the calling line, means for connecting the calling line through the connecting switch to the testing switch, means including the calling device effective after the establishing of connection with the testing

switch for at will initiating the automatic operation of the testing switch, means exclusive of the calling device for maintaining the automatic operation of the testing switch after its initiation to restore the switch to the position held before the said initiation, means for adapting the testing switch to be subject to step-by-step control from the calling device effective consequent upon the said restoration, and means whereby then operating the calling device will operate the testing switch step-by-step.

25. In mechanism for testing the busy or idle state of each trunk of a group of trunks, test contacts individual to each trunk accessible to a test wiper of the mechanism, means for initiating the functioning of the mechanism, and means for setting up a condition in the mechanism controlled by the test contacts found busy but not controlled by the test contacts found idle which will index the number of busy trunks in the group.

26. In a telephone system a plurality of telephones and cooperating switches, a trunk consisting of a first and a second branch normally accessible to the telephones, a tone source, a setting device, means in control of a telephone on one of the said branches for setting up a condition in the setting device indexing the number of telephones on the other said branch, and means including the setting device whereby the tone will be applied audible through the controlling telephone only, verifying the number of telephones connected to the other said branch.

27. In a telephone system a plurality of telephones and cooperating switches, a trunk consisting of a first and a second branch normally accessible to the telephones, a tone source, a setting device, means in control of a telephone on one of the said branches for setting up a condition in the setting device indexing the number of telephones on the other said branch, and means including the setting device whereby the tone will be applied audible through the controlling telephone only, verifying the number of telephones connected to the other said branch, if the said set-up condition indexes the number of telephones actually connected to the other said branch.

28. In a telephone system a plurality of telephones and cooperating switches, a trunk consisting of a first and a second branch normally accessible to the telephones, a tone source, a setting device, means in control of a telephone on one of the said branches for setting up a condition in the setting device indexing an arbitrary number of telephones which may be connected to the other said branch, means including the setting device whereby the tone will be applied audible through the controlling telephone to verify the number of telephones connected to the other said branch if the said set up condition

indexes the number of telephones actually connected to the other said branch, and means for disassociating the tone source.

29. In a telephone system a plurality of telephones and cooperating switches, a trunk consisting of a first and a second branch normally accessible to the telephones, a tone source, a setting device, means in control of a telephone on one of the said branches for setting up a condition in the setting device indexing an arbitrary number of telephones which may be connected to the other said branch, and means including the setting device whereby the tone will be applied audible through the controlling telephone to verify the number of telephones connected to the other said branch if the set up condition indexes the number of telephones actually connected to the other said branch.

30. In a telephone system a testing telephone, a line leading from the testing telephone to a first automatic switch, the switch for testing the normal and abnormal state of a plurality of test contacts, a second switch operated by the said first switch in correspondence with the number of test contacts found abnormal by the said first switch, and means including the first switch controlled from the testing telephone operable at will for ascertaining the number of test contacts found abnormal by the said first switch.

31. In a testing system a testing station, a line leading from the testing station to a first automatic switch, the switch for testing the normal and abnormal state of a plurality of test contacts, a second switch operated by the said first switch in correspondence with the number of test contacts found abnormal by the said first switch, and means operable at will over the said line after the testing operations have been completed for indexing the number of test contacts found abnormal by the said first switch.

32. In a testing system a testing station, a mechanism primarily controlled from the said station for thereafter automatically testing test contacts wherein each said test contact manifests one of two conditions respectively, test contacts manifesting the two conditions, each said test contact manifesting one said condition, means for automatically setting up a condition in the mechanism depending upon the number of test contacts tested which manifest a predetermined one of said two conditions, and means including the said mechanism for evidencing only the number of test contacts tested which manifest the said predetermined condition.

33. In a telephone system a testing station, a mechanism primarily controlled from the said station for thereafter automatically testing line busy-test contacts of telephone lines wherein each said test contact manifests a busy or an idle condition respectively, test contacts manifesting the two conditions,

means for automatically setting up a condition in the mechanism depending upon the number of test contacts tested which manifest a busy condition, and means including the 5 said mechanism for evidencing only the number of test contacts tested which manifest the busy condition.

34. In a telephone system a testing station, a mechanism primarily controlled from the said station for thereafter automatically testing line busy-test contacts of telephone lines wherein each said test contact manifests a busy or an idle condition respectively, test contacts manifesting the two conditions, and 10 means for automatically setting up a condition in the mechanism depending upon the number of test contacts tested which manifest a busy condition.

35. In a telephone system a testing station, 20 a mechanism primarily controlled from the said station for thereafter automatically testing line busy-test contacts of telephone lines wherein each said test contact manifests a busy or an idle condition respectively, test contacts manifesting the two conditions, and 25 means for automatically setting up a condition in the mechanism depending upon the number of test contacts tested which manifest a busy condition to indicate at the testing station the number of lines found busy.

36. In a telephone system a testing station, a line, a mechanism primarily controlled over the line from the said station for thereafter testing line busy-test contacts of a group of 35 telephone lines automatically wherein each said test contact manifests a busy or an idle condition respectively, a tone source, test contacts manifesting the two conditions, and means for automatically setting up a condition 40 in the mechanism depending upon the number of test contacts which manifest a busy condition when tested to apply the tone source over the line to the testing station to indicate the number of busy lines tested.

37. In a telephone system a testing station, 45 a mechanism primarily controlled from the said station for thereafter automatically testing test contacts wherein each said test contact manifests one of two conditions respectively, 50 test contacts manifesting the two conditions, each said test contact manifesting one said condition, and means for automatically setting up a condition in the mechanism depending upon the number of test contacts tested which manifest a predetermined one of said 55 two conditions.

38. In a testing system a testing station, a mechanism primarily controlled from the said station for thereafter automatically testing 60 test contacts wherein each said test contact manifests one of a plurality of conditions respectively, test contacts manifesting the plurality of conditions, each said test contact manifesting one said condition, and means for automatically setting up a condition in 65

the mechanism depending upon the number of test contacts tested which manifest a predetermined one of said plurality of conditions.

39. In a testing system a testing station, a 70 mechanism primarily controlled from the said station for thereafter automatically testing test contacts wherein each said test contact manifests one of a plurality of conditions respectively, test contacts manifesting the plurality of conditions, means for automatically setting up a condition in the mechanism depending upon the number of test contacts tested which manifest a predetermined one of said plurality of conditions, and means including the said mechanism for evidencing only the number of test contacts tested which manifest the said predetermined condition.

40. In a testing system a group of busy-test contacts corresponding respectively to the lines of a group of busy and idle lines, a test mechanism, means for causing the test mechanism to operate whereby to test the said contacts, and means for indicating the number of busy lines in the group.

41. In a telephone system a trunk line, a plurality of connection points at which connection can be made to the trunk line from connecting lines, a plurality of said connecting lines, means on the respective said connecting lines for connecting the said connecting lines to the trunk line through the connection points respectively, the number of said connecting lines possible of connection to the trunk line not exceeding the number of said connection points, and means controlled from one of said plurality of connecting lines connected to the trunk line to indicate how many connecting lines are then connected to the trunk line and to bar the trunk line from 90 being thereafter being connected to by a connecting line through an unconnected connection point.

42. In a telephone system a trunk line, a plurality of connection points at which connection can be made to the trunk line from connecting lines, a plurality of said connecting lines, means for connecting the said connecting lines to the trunk line through the connection points respectively, the number of said connecting lines possible of connection to the trunk line not exceeding the number of said connection points, a lesser number of connecting lines being connected to the trunk than there are connection points, and means controlled from one of said plurality of connecting lines connected to the trunk line to indicate how many lines are connected to the trunk line through an unconnected connection point.

43. In a telephone system a trunk line, a plurality of connection points at which connection can be made to the trunk line from connecting lines, a plurality of said connecting lines, means for connecting the said con-

- necting lines to the trunk line through the connection points under control of the respective connecting lines, the number of said connecting lines possible of connection to the trunk line not exceeding the number of said connection points, a lesser number of connecting lines being connected to the trunk than there are connecting points, and means controlled from one of said plurality of connecting lines connected to the trunk line to indicate how many lines are connected to the trunk line.
44. In a telephone system a trunk line, a plurality of connecting points at which connection can be made to the trunk line from connecting lines, a plurality of said connecting lines, means for connecting the said connecting lines to the trunk line through the connection points under automatic switch control from the respective connecting lines, a lesser number of connecting lines being connected to the trunk line than there are connecting points, and means to indicate how many lines are connected to the trunk line.
45. In a telephone system a trunk line, a plurality of connecting points at which connection can be made to the trunk line from connecting lines, a plurality of connecting lines, means for connecting one or more of the said connecting lines to the trunk line through a corresponding number of connection points under automatic switch control from the respective connecting lines, a tone source corresponding to each plurality of connecting lines which may be connected to the trunk line, and means for automatically applying the tone source indicative of the number of connecting lines connected to the trunk line.
46. In a telephone system, a calling subscriber's line, an automatic switch associated therewith, called lines accessible thereto, a calling device under the control of said calling subscriber for operating said switch into engagement with one of said called lines without making the same busy, and means responsive to the reoperation of said calling device for preventing another connection being established with the connected line.
47. In a telephone system, a calling subscriber's line, an automatic switch associated therewith, called lines accessible thereto, a calling device under the control of said calling subscriber for operating said switch into engagement with one of said called lines with-

out making the same busy, and a relay energized in response to the reoperation of said calling device for applying a busy potential to said called line. 55

48. In an automatic telephone system, a conference line, branches of said conference line, a plurality of calling telephone lines, automatic switches, means for automatically operating certain of the switches to connect corresponding said telephone lines in talking relation with individual branches of said conference line, means whereby all said connected telephone lines thereby become in mutual talking relation, and means operated over one of said telephone lines connected for preventing an additional said telephone line from 70 becoming in talking relation with an unconnected branch of the conference line. 65

49. In an automatic telephone system, a conference line, branches of said conference line, a plurality of calling telephone lines, automatic switches, means for automatically operating certain of the switches to connect corresponding said telephone lines in talking relation with individual branches of said conference line, means whereby all said connected telephone lines thereby become in mutual talking relation, means operated over one of said telephone lines connected for preventing an additional said telephone line from 75 becoming in talking relation with an unconnected branch of the conference line means whereby one of the connected lines can be disconnected from the conference line branch to which it was connected, and means for preventing a substituted connection over the latter said branch without specific directive operation therefor. 80

50. In a telephone system, a group of busy-test contacts corresponding respectively to the lines of a group of busy and idle lines, a test mechanism, means for causing the test mechanism to operate whereby to test the said contacts, a plurality of tone sources, and means for applying any one of said tone sources to produce an audible sound 95 wherein the specific said tone source applied will be determined by the number of lines which are busy in the group at the time the test mechanism is operated. 100

In witness whereof, I hereunto subscribe my name this 21st day of February, A. D. 1921. 105

HERBERT M. FRIENDLY.
